[57] **CLAIM**

The ornamental design for a portable double-sided flip-bins storage unit, as shown and described.

DESCRIPTION

FIG. 1 is a first side view of a portable double-sided flip-bins storage unit showing my new design;
FIG. 2 is a second side view thereof;
FIG. 3 is a front view thereof;
FIG. 4 is a rear view thereof;
FIG. 5 is a top view thereof;
FIG. 6 is a bottom view thereof;
FIG. 7 is a perspective view from the rear thereof, it being in an open position;
FIG. 8 is a perspective view from the front thereof, it being in an open position; and,
FIG. 9 is a perspective view thereof, it being in a closed state, with the flip-bins being in an open state.
